121,051

DESIGN FOR A TEXTILE FABRIC

John L. Walther, New York, N. Y.

Application May 3, 1940, Serial No. 92,104

Term of patent 3½ years

To all whom it may concern:

Be it known that I, John L. Walther, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design comprises a multiplicity of small mound-like puffs of yarn arranged in substantially vertical rows on a sheer background as shown.

I claim:

The ornamental design for a textile fabric, substantially as shown and described.

JOHN L. WALThER.
